HUBERT HOPKINS, OF ST. LOUIS, MISSOURI, ASSIGNOR TO MOON-HOPKINS BILLING MACHINE COMPANY, OF ST. LOUIS, MISSOURI, A CORPORATION OF MISSOURI.

CALCULATING-MACHINE.

1,089,559.

Specification of Letters Patent. Patented Mar. 10, 1914.

Application filed July 2, 1909. Serial No. 505,712.

To all whom it may concern:

Be it known that I, HUBERT HOPKINS, a citizen of the United States, residing at St. Louis, Missouri, have invented a certain 5 new and useful Improvement in Calculating-Machines, of which the following is a full, clear, and exact description, such as will enable others skilled in the art to which it appertains to make and use the same, reference being had to the accompanying drawings, forming part of this specification, in which—

Figure 1 is a side elevational view, showing the subtraction key and its connections 15 in normal position. Fig. 2 is a top plan view of the result keys and their connections. Fig. 3 is a view similar to Fig. 1, showing the parts in the position they occupy when the subtraction key is operated. Fig. 4 is a 20 top plan view of a modified form. Fig. 5 is a front elevational view of said modified form.

This invention relates to a new and useful improvement in calculating machines of that 25 type illustrated in Belgian Patent No. 202,081, dated August 21, 1907, which construction is also illustrated in United States application filed by me January 14, 1904, serially numbered 189,031 and filed by me 30 April 9, 1906, serially numbered 310,739.

The object of my present invention is to provide the calculating machine illustrated in the aforesaid patent and applications with a subtraction key by which it is possible to subtract one number from another, and which subtraction feature is a valuable function of the machine in computing bank balances, etc.

My present invention is designed as a very 40 simple attachment to the calculating machine illustrated in the aforesaid patent and applications, and consists of a key which may be designated as the subtraction key, which key, when operated, throws out the 45 tripping pawls of the carrying mechanism in the forward totalizers and trips the carrying pawls of the rear totalizer, or vice versa. To save the extra operations of depressing the T or total key, and the P or product 50 key, of my aforesaid machine, the subtraction key is made to depress these keys jointly when the machine is operated to perform subtractive computations. In the operation of the computing machine illustrated 55 in the accompanying drawings, as is fully

set forth in said Belgian patent referred to, items can be set up directly from the keyboard into the forward totalizer represented by the wheels 119 or directly into the rear totalizer represented by the wheels 268. In this way, either the forward or rear totalizer may be used as a primary totalizer for the reception of various items. The registering wheels 268 are also identified with the multiplying mechanism, but as the 65 operation of multiplying is not involved in my present invention, I shall not refer to the same here.

To obtain a total from the forward totalizer wheels 119, the T or total key is depressed, which causes the wheels 119 to mesh with the racks 100 before the handle 79 is pulled forward, and, consequently, in a total-taking operation the racks 100 with their carried printing type move forwardly 70 to represent the total reversely rotating wheels 119 until they are arrested by the tripping pendants 121 identified with the carrying mechanism, which tripping pendants determine the zero position of the 75 wheels 119.

To obtain a total from the rear totalizer wheels 268, the P or product key is depressed, which causes said wheels 268 to mesh with the racks 100 and when the handle 79 is pulled forward, said wheels are reversely rotated until they are arrested in their zero position by pendants 121¹ of the carrying mechanism, which correspond to the pendants 121 which coöperate with 80 wheels 119. The total-taking operations from both front and rear totalizers is precisely the same so far as reversely rotating the accumulator wheels to their zero position where they are arrested and in which zero 85 position the printing type are set up in the printing line to represent the total.

In the operation of subtracting, the subtrahend is set up in the rear totalizer wheels 268 in a manner fully set forth in my aforesaid Belgian patent, but which may briefly be described as follows: If the subtrahend is composed of a number of items, they are successively set up on the keyboard, the D-key depressed and the handle pulled to introduce each item. The total of the items, or a single number, standing in the wheels 268, represents the subtrahend. The minuend, the number to be subtracted from, is set up in the usual way in the wheels 119, and 100 105 110

may be composed of a series of items or a single number. In the usual way of introducing these numbers into the machine, the minuend, or larger number, is introduced into the forward totalizer, and the subtrahend, or smaller number, is introduced into the rear totalizer. It is, of course, possible, and in some operations necessary, where the minuend and subtrahend are composed of a series of items, to introduce said items either successively or alternately into the forward or rear totalizer, composing the minuend or subtrahend, depending in which column the item introduced belongs.

15 The subtraction key is represented by the numeral 500 and is like the other result keys of the machine, being arranged in the keyboard and connected to a bell crank lever 501. To this bell crank lever is arranged a 20 rod or wire 502 connected to a lever 503. This lever 503 has its upper end bent behind the group of bell crank levers 303, 341, 172, 227 and 326, identified with the result keys P, D, T, R, and E respectively.

25 The rearward extension of lever 503 is provided with forwardly extending projections which are located immediately behind levers 303 identified with the P-key, and 172, identified with the T-key. When the subtraction key is pressed, as shown in Fig. 2, the bell crank levers 303 and 172 are actuated the same as if the P and T-keys had been operated, and, consequently, the register wheels 268 and 119 are thrown into mesh with the racks 100.

30 Lever 503 is in the form of a bell crank lever and is connected by a rod 504 to an arm 505 fixed on a rod 506 on which is also fixed an arm 507 connected by a link 508 to a lever 509, which lever carries a rod 510 arranged under the ends of the restraining bars 127 identified with the carrying mechanism for the rear totalizer wheels 268.

35 The arm 507 carries a pin 507* which is arranged behind an arm 511 so that when the subtraction key is operated, arm 507 has an initial movement before the pendants 121 of the forward totalizer are moved forwardly out of the path of the tripping projections on the wheels 119.

40 When the subtraction key is pressed, all of the carrying toothed segments 129 identified with the rear totalizer wheels 268 are initially tripped and operate to add "1" to every one of said wheels except the wheel 268 identified with the units column, this addition, resulting from the operation of the carrying mechanism, occurring before the wheels 268 are depressed sufficiently far as 45 to be beyond the control of the toothed segments 129. In other words, operating the subtraction key has the effect of initially tripping the carrying mechanism to actuate all of the wheels 268 to which numbers 50 may be carried from a lower order, just the

same as if said carrying mechanism had been operated in the usual way.

Assuming for the purpose of illustration that it is desired to subtract 478 from 952. The subtrahend 478 may be introduced into the rear totalizers 268 either as a single number or as a series of items successively introduced therein. The minuend 952 may stand in the forward totalizers, having been introduced therein as a single number 70 or as a series of smaller numbers. When the subtraction key is depressed, the tripping of the carrying mechanism identified with the tens, hundreds, etc., wheels 268 causes said wheels to stand thus:

$$\begin{array}{r}
 0,000,478 \\
 1,111,110 \\
 \hline
 1,111,588
 \end{array}$$

80

85

In other words, when the wheels 268 are in mesh with the carrying segments 129 and said carrying segments are operated as in carrying, by the depression of the subtraction key, "1" is added to each of the wheels 90 268 of a higher denomination than the units wheel. The reason why the units wheel is not operated is due to the fact that there is no lower order than the units wheel and consequently nothing can be carried to the 95 units wheel as the units wheel does not cooperate with an actuating carrying segment 129.

The wheels of the rear totalizer standing at 1,111,588 will, when the subtraction key 100 is fully depressed, be thrown into mesh with the racks 100, as will also the wheels 119. When the pin 507* engages the arm 511 the wheels 119 will have passed out of mesh with their toothed segments 129, and the 105 pendants 121 identified with the wheels 119 will be moved out of the zone of influence of the tripping projections on said wheels, before said wheels are finally meshed with the racks 100. Upon pulling the handle 79, 110 the racks 100 will be moved forwardly, reversely rotating both sets of wheels 268 and 119. As the pendants 121 have been moved out of the paths of the tripping projections on the wheels 119, said wheels can reversely 115 rotate past their zero position, as there is nothing to arrest or stop them when they reach such zero position. It is different, however, with respect to the wheels 268. The wheels 268 will be arrested by their co-operating pendants 121 in their zero position.

To simplify the further description of operation, I will regard the minuend as not being in the wheels 119, and consider said 125 wheels as standing at zero.

In transferring the excessive complement of the subtrahend, the units wheel 268, which stood in the eighth position, will be reversely rotated a distance of eight teeth, causing 130

the units wheel 119, through the rack 100, to be reversely rotated eight teeth, so that the units wheel 119 will stand at "2", which is the complement of 8, plus 1. That is, the 5 true complement of 8 is 1, but if it is considered that the pendant 121 with which the zero stop and tripping projection 120, on wheels 119, coöperate, is a "point", the tooth immediately thereunder, which is the 10 "nine" tooth, will pass that "point" as will also the "eight", "seven" "six" "five" "four" "three" and "two" teeth (eight teeth in all) in a reverse direction, leaving said units wheel standing at "2". The true 15 complement of 8 is 1, but 1 added to 1 makes 2, and 2 is the complement of 8, plus 1, i. e. 1 and 1=2. The tens wheel 268, which also stood in the eighth position, will, through its rack 100, reversely rotate the 20 tens wheel 119 a distance of eight teeth so that it will likewise stand at "2", which is the complement of 8, plus 1. The hundreds wheel 268 which stood at 5, by its reverse rotation through the rack 100, has reversely rotated the hundreds wheel 119 a 25 distance of five teeth so that said hundreds wheel 119 stands at 5, which is the complement of 5 plus 1. The wheels 268 in the thousands and higher denominations which 30 stood at "1", have reversely rotated the corresponding wheels 119 a distance of one tooth so that said wheels stand at 9, 9 being the complement of 1 plus 1. The wheels 119 will thus stand at 9,999,522. It will be 35 seen that this number is an excessive complement of the subtrahend; that is, it is a larger complement by the addition of "1" to each denomination higher than the units column. As we have treated the wheels 119 40 as standing at zero, the minuend 952 is now added to the excessive complement of the subtrahend standing in the wheels 119, and the said wheels 119 stand to represent 0,000,474, which is the correct remainder 45 after subtracting 478 from 952.

The remainder can be retained in the machine or be transferred to any particular totalizer in the manner described in my Belgian patent aforesaid. 50 It is obvious that if it is desired to introduce the minuend into the rear totalizer and the subtrahend into the forward totalizer, this could be done simply by arranging the proper mechanism to first trip the forward 55 totalizer and then to throw the pendants 121 of the rear totalizer out of coöoperative relation thereto, in the manner heretofore described.

In Figs. 4 and 5 I have shown means for 60 first tripping, and then throwing the pendants 121 out of relation to the forward totalizer, as a modification of my invention. In this modification, no means are necessary for tripping the pendants of the rear totalizer.

I will now describe how the machine can be operated to perform the computation of subtraction without disturbing the pendants 121 of the rear totalizer. The minuend, I 70 will assume, stands in the forward totalizer wheels 119, which minuend, for illustration, is 1234. The subtrahend 478 stands in the rear totalizer wheels 268. These are the footings of debit and credit columns. The credit, 478, is printed as a footing and retained in the rear totalizer. The debit, 1234, 75 is printed as a footing to the column accumulated in the forward totalizer. To secure the balance, or remainder, the subtraction key is depressed and this subtraction key may, coincidentally, depress the P or product key and the T or total keys, as heretofore described, or the said keys may be depressed as a separate operation. I prefer, 80 however, to employ the arrangement heretofore described and depress said keys by the 85 operation of the subtraction key.

The subtraction key and its connections 500, 501, 502, 503, 504, 505, 506, 507 and 507' 90 may be the same as heretofore described, but the parts 508, 509 and 510 heretofore described are omitted in this modification.

The depression of the subtraction key first disengages the wheels 119 from the segments 129, then trips the said segments and at the same time moves the pendants 121 out of operative relation to the tripping projections on the wheels 119; and finally causes said pendants to mesh with the racks 100 in exactly the same manner heretofore described. The wheels 268 and 119 being now in mesh with the racks 100, will, when the handle is pulled forward, cause the wheels 119 to be reversely rotated until the wheels 268 are arrested in their zero position. In 95 the example under consideration, the correct remainder after subtracting 478 from 1234, is 756. Assuming that the wheels 119 stand at zero, the reverse rotation of the units wheel a distance of eight teeth will cause 100 said wheel to stand at 2; the reverse rotation of the tens wheel a distance of seven teeth will cause said wheel to stand at 3; and the reverse rotation of the hundreds wheel a distance of four teeth will cause said 105 wheel to stand at 6, so that the wheels 119 will stand to represent 0,000,632.

When the handle reaches the forward limit of its movement and starts to move rearwardly, the beginning of said rearward movement occasions the lifting of the frames carrying the front and rear totalizers so that the wheels 119 and 268 are disengaged from the racks 100. When the handle is in its forward position, the cam 82 is rocked forward and the inclined face 146 thereof is in front of the pin 141 of the tappet 140 on the bar 138. The bar 138 is connected to a rod 137 carried by appropriate rock arms, which rod 137 is arranged under the tail 110 115 120 125 130 135 140 145 150 155 160 165 170 175 180

pieces 131 of the toothed segments 129. The vibration of rod 138 causes a vertical movement of the rod 137 and effects the restoration of the tripped toothed segments 129. Thus, when the handle starts to move rearwardly, it first raises the wheels 119 and 268 out of engagement with the racks 100 and into engagement with their respective toothed segments 129. The toothed segments 129 identified with the rear totalizers occupy a normal position, while those identified with the carrying mechanism of the front totalizers have been tripped and lie in an abnormal position, so that when the wheels 119 are thrown into mesh therewith and the bar 138 is vibrated to restore the toothed segments, the wheels 119 will be reversely rotated a distance of one tooth so that said wheels now stand to represent 9,999,522. It will be noted in the above description that the units wheel has not been reversely rotated one tooth, but still stands at "2", because said units wheel does not have a complementary carrying segment 129. As the cam plates 82 and 109 are shifted laterally, upon the depression of the P or T keys for several purposes, among which may be mentioned that such lateral movement prevents coöperation between the cam 82 and the pin 141 on the tappet 140, it is obvious that some means must be provided, when utilizing the carrying mechanism in the subtraction operation as above indicated, to maintain coöperative relation between the pin 141 and the cam 82. In the machine of my Belgian patent aforesaid, one of the purposes of shifting the cam 82, as before stated, was to prevent coöperation between the cam 82 and the pin 141, as in the taking of a total, if any of the toothed segments 129 were displaced the restoration thereof in the manner in which I propose to utilize such restoration in subtracting operations, would interfere with the total-taking operations. 515 indicates a lever pivotally mounted on the plate 115 and whose rear end is bifurcated so as to engage the bar 138. This lever has a beveled forward end which operates with a downward extension 511 of the arm 511. Thus, when the subtraction key is depressed to trip the toothed segments 129, etc. the lever 515 is operated to move the bar 138 and its carried tappet laterally together with the lateral shifting movement of the cam plate 82 so as to maintain coöperative relation between said cam plate and the pin 141. Means must also be provided to hold the arm 138 and its carried parts in relation to the plate 82 during the full movement of the handle so that the pin 141 may, at the proper time, drop behind the shoulder 145 on the cam 82. This is accomplished by means of a restraining pawl 516 pivotally mounted under the plate 115 and provided with a shoulder which is lifted to engage the lever 515 and hold said lever in its shifted position during the operation of the handle.

To release the lever 515, an extension 517 is provided on the end of the restraining pawl, which extension lies under a vibrating plate 93^b. Plate 93^b is vibrated at every stroke of the handle and just previous to the time that the handle reaches the rearward limit of its movement on each stroke. A spring 518 tends to hold the shoulder of the restraining pawl to its work. A spring 519 tends to restore the lever 515. Spring 98, which supports the vibrating plate 93^b, which plate restores the stop pins 93, 80 is strong enough to support the parts which it carries.

In the operation of the above described parts, a depression of the subtraction key shifts the cam plate 82 and with it the bar 138 and its carried parts through the medium of the lever 515. The restraining pawl 516 engages the lever and holds it in its shifted position until the handle approaches the rearward limit of its movement, at which time the plate 93^b is vibrated and said plate, striking the extension 517, will depress the restraining pawl. The spring 519 restores lever 515 and the bar 138 to normal position, and said lever 515 in its home position lies above the shoulder of the restraining pawl 516 as shown.

To return to the operation of subtracting 478 from 1234, I left the wheels 119 standing at 9,999,522, which represents their relative positions after the handle had started on its rearward movement and had restored the toothed segments 129 so as to reversely rotate all of the wheels 119, except the units wheel, a distance of one tooth. If we now add the minuend to the wheels 119, we will find that said wheels will exhibit the correct remainder, as follows:

9,999,522	110
0,001,234	
—————	
0,000,756	

In practice, in both forms of my invention, I prefer to add the minuend to the excessive complement of the subtrahend which has been introduced into the wheels 119, for the reason that by so doing the wheels of higher denomination at the left are actuated by the carrying mechanism by the addition of "1" thereto, so that all of the 9's are eliminated, and said wheels will stand at zero, as illustrated in the above example.

Having thus described my invention, what I claim is:

1. In a calculating machine, the combination of two totalizers, means for connecting them together, carrying mechanism coöperating with one of said totalizers and means

- for operating said carrying mechanism to carry "1" in each of the totalizer wheels above the units wheel said means being operable independently of the totalizer wheels.
5. 2. In a calculating machine, the combination of two totalizers, means for connecting said totalizers whereby a number may be transferred from one totalizer to the other, a carrying mechanism coöperating with the totalizer from which the number is to be transferred, and means for operating said carrying mechanism to actuate certain of the wheels of said totalizer before a number is transferred therefrom, said means being operable independently of the totalizer wheels.
10. 3. In a calculating machine, the combination of a totalizer, a carrying mechanism coöperating therewith, and means independent of the totalizer wheels for operating said carrying mechanism to effect carrying.
15. 4. In a calculating machine, the combination of a totalizer whose wheels are provided with tripping projections, carrying mechanism which is operated by said tripping projections, and means independent of said tripping projections for operating said carrying mechanism to effect carrying.
20. 5. In a calculating machine, the combination of a totalizer, carrying mechanism coöperating therewith, means on the totalizer wheels for operating said carrying mechanism to individually carry from one wheel to the next, and means operable independently of said totalizer wheels for operating all of said carrying devices collectively to effect carrying.
25. 6. In a calculating machine, the combination of a totalizer, carrying mechanism coöperating therewith, plural means for operating said carrying mechanism individually and collectively, the individual operating means being operable by the totalizer wheels, and the collective operating means being operable at the will of the operator; said latter means effecting simultaneously carrying of all of the wheels above the units wheel.
30. 7. In a calculating machine, the combination of a totalizer, carrying mechanism coöperating therewith, plural means for operating said carrying mechanism to actuate said totalizer wheels above the units wheel, one of said means being controlled by said wheels and a key operated rod for controlling the other of said means.
35. 8. In a calculating machine, the combination of a totalizer, carrying mechanism therefor, means operating independently of the totalizer wheels for effecting the operation of carrying in said carrying mechanism entirely across the totalizer, and a key in the keyboard for operating said means.
40. 9. In a calculating machine, the combination of a totalizer, carrying mechanism coöperating therewith, means operating independently of the totalizer wheels for effecting the operation of carrying in said carrying mechanism entirely across the totalizer, and means within convenient reach of the operator for operating said means.
45. 10. In a calculating machine, the combination of a totalizer, the carrying mechanism therefor, and means for first operating all of the carrying devices, simultaneously, and then rendering said carrying devices inoperative.
50. 11. In a calculating machine, the combination of a totalizer, a carrying mechanism therefor and a key within convenient reach of the operator for first operating all of said carrying devices, simultaneously, and then rendering all of said carrying devices inoperative.
55. 12. In a calculating machine, the combination of a totalizer whose wheels are provided with tripping projections, carrying mechanism coöperating therewith, and means for first operating and then moving the coöperating parts of said mechanism beyond the control of said tripping projections.
60. 13. In a calculating machine, the combination of a totalizer whose wheels are provided with tripping projections, carrying mechanism having a plurality of parts coöperating with said tripping projections, and means for first operating and then moving all of said coöperating parts beyond the control of said tripping projections.
65. 14. In a calculating machine, a totalizer whose wheels are provided with tripping projections, carrying mechanism having parts coöperating with said tripping projections, a member in control of all of said parts, and a key or lever within convenient reach of the operator for operating said member to operate said carrying mechanism.
70. 15. In a calculating machine, the combination of two totalizers and their respective carrying mechanisms, of means under control of the operator for operating the carrying mechanism of one of said totalizers and simultaneously rendering inoperative the carrying mechanism of the other totalizer.
75. 16. In a calculating machine, the combination of two totalizers with their respective carrying mechanisms, means under control of the operator for operating the carrying mechanism of one totalizer, rendering the carrying mechanism of the other totalizer inoperative, and connecting said totalizers.
80. 17. In a calculating machine, the combination of a subtrahend register, of means whereby "1" may be added in each register wheel above the units wheel, a minuend register, and means for connecting the two registers whereby the minuend register may be reversely rotated and the excessive complement of the subtrahend registered therein.
85. 90. 95. 100. 105. 110. 115. 120. 125. 130.

18. In a calculating machine, the combination of a subtrahend register, means for introducing one or a series of numbers composing the subtrahend, a minuend register, means for introducing into said register one or a series of numbers composing the minuend, and means whereby an excessive complement of the subtrahend is obtained and subtracted from the minuend in the minuend register. 70
19. In a calculating machine, the combination of a subtrahend register, a minuend register, means whereby numbers may be singly, successively or alternately introduced into and added in said registers to compose the subtrahend and minuend respectively, and means for automatically adding "1" to the complement of the subtrahend and the minuend to obtain the remainder. 75
20. In a calculating machine, the combination of a subtrahend and a minuend register, of means for introducing and adding together various numbers in said registers to compose the subtrahend and minuend respectively, and means for obtaining an excessive complement of the subtrahend and subtracting it from the minuend to obtain the correct remainder. 80
21. In a calculating machine, the combination of a subtrahend register and a minuend register, means whereby numbers may be added together therein to compose the subtrahend and minuend, means for adding "1" to each of the subtrahend register wheels except the units wheel, and means for connecting said two registers together and reversely rotating them until the wheels of the subtrahend register reach zero, in which position the correct remainder will be contained in the minuend register. 85
22. In a calculating machine, the combination of a subtrahend and a minuend register, carrying mechanism co-operating therewith, means for adding numbers together in said registers to compose the subtrahend and minuend respectively, means for operating the carrying mechanism of the subtrahend register whereby "1" will be added to each of said register wheels except the units wheel, said means rendering the carrying mechanism of the minuend register inoperative, and a power shaft for reversely rotating the connected registers until the subtrahend register wheels reach zero, in which position the correct remainder will be represented in the minuend register wheel. 90
23. In a calculating machine, the combination of two independent registers either of which may be used as a primary register to add numbers, means for separately obtaining totals from said registers, and a subtraction key in control of both of said total-taking mechanisms. 95
24. In a calculating machine, the combination of two independent registers each of which is primary in character and capable of adding numbers together, independent keys for separately obtaining totals from said registers, and a subtraction key in common control of said total keys. 100
25. In a calculating machine, the combination of two independent registers and their carrying mechanisms, of digit keys through which numbers are introduced into the machine to be registered in said registers, means for selectively determining the particular register in which any given number so introduced into the machine shall be registered, total keys in control of said registers respectively whereby separate totals may be obtained therefrom, a subtraction key in common control of said total keys, and means operated by said subtraction key whereby the carrying mechanism of one of said registers is operated and the carrying mechanism of the other of said registers is rendered inoperative. 105
26. In a calculating machine, the combination of two registers, racks for actuating said registers, means whereby either of said registers may be made primary in character to register and add various numbers, and a subtraction key for simultaneously engaging said registers with said racks whereby the excessive complement of the subtrahend may be introduced into the other or minuend register to obtain the correct remainder. 110
27. In a calculating machine, the combination of two independent registers, means for separately obtaining totals from said registers, and means in control of both of said total-taking mechanisms. 115
28. In a calculating machine, the combination of two registers, total-taking mechanisms in control thereof, and means in common control of said total-taking mechanisms. 120
29. In a calculating machine, the combination of two registers and means in control thereof for coupling said registers together and automatically adding "1," said means automatically subtracting "1" from the minuend register when said registers are actuated in subtracting operation. 125
30. In a calculating machine, the combination of two registers and means for coupling said registers together, said means, when said registers are operated after being coupled together, automatically causing all the wheels of the minuend register except the units wheel to be reversely rotated one tooth in excess of the position occupied by the controlling subtrahend wheel. 130
31. In a calculating machine, the combination of a register and its carrying mechanism, a main shaft which operates and restores said carrying mechanism, and means for operating said carrying mechanism while said main shaft is at rest. 135
32. In a calculating machine, the combination of two independent registers each of which is primary in character and capable of adding numbers together, independent keys for separately obtaining totals from said registers, and a subtraction key in common control of said total keys. 140

- 5 nation of a register and its carrying mechanism, and means for operating said carrying mechanism to actuate all the wheels above the units wheel and then moving it beyond the control of said register.
33. In a calculating machine, the combination of a main shaft, a register, a carrying mechanism, and means for positioning parts of said carrying mechanism while said
- 10 main shaft is at rest, said positioned parts being operated by the main shaft when in action.
34. In a calculating machine, the combination of a minuend register containing a
- 15 relatively large number, a subtrahend register containing a relatively small number, and means whereby the carrying mechanism of the subtrahend register is operated, and said register placed in control of the minu-
- 20 end register in subtracting operations, so as to produce the correct remainder.
35. In a calculating machine, the combination of a minuend register and its carrying mechanism, a subtrahend register, and
- 25 means whereby the carrying mechanism of the minuend register is rendered inoperative, and said register placed under control of the subtrahend register in subtracting opera-
- 30 tions.
36. In a calculating machine, the combination of two registers racks, and means for engaging said registers with said racks whereby one of said registers is placed in control of the other for the purpose of in-
- 35 troducing the complement of the subtrahend into the controlled register, less "1" in all denominations except the units denomina-
37. In a calculating machine, the combination of two registers and their carrying mechanisms, and means for rendering the carrying mechanism of one register inoperative; said means placing said register under control of the other register and its
- 40 carrying mechanism.
38. In a calculating machine, the combination of two registers and their carrying mechanisms, means for tripping the carrying mechanism of one register independently
- 45 of any movement of its co-operating register wheels, and means for coupling said registers together whereby one of said registers and its carrying mechanism is in control of the other register.
39. In a calculating machine, the combination of two registers and their carrying mechanism, a subtraction key, and means controlled by said subtraction key for operating the carrying mechanism of one of
- 50 said registers.
40. In a calculating machine, the combination of two registers and their carrying mechanism, a subtraction key, and means controlled by said subtraction key for ren-
- 5 dering the carrying mechanism of one of 65 said registers inoperative.
41. In a calculating machine, the combination of two registers and their carrying mechanism, a subtraction key, and means controlled by said subtraction key for operating the carrying mechanism of one of 70 said registers and coupling said registers together.
42. In a calculating machine, the combination of two registers and their carrying mechanism, a subtraction key, and means controlled by said subtraction key for coupling said registers together and rendering one of said carrying mechanisms inoperative.
43. In a calculating machine, the combination of two registers and their carrying mechanism, a subtraction key, and means controlled by said subtraction key for operating the carrying mechanism of one of 85 said registers, coupling said registers together and rendering the carrying mechanism of the other register inoperative.
44. In a calculating machine, the combination of two sets of denominational wheels, 90 one set of wheels being in control of the other, denominational racks, means for differentially positioning said denominational racks, a key board whereby a number set up on said key board may be subtracted 95 from a number previously introduced into the controlled set of wheels by reversely rotating said wheels, and means for disabling the tripping pawls of the carrying mechanism whereby said wheels may be reversely rotated past their zero position, if necessary.
45. In a calculating machine, the combination of differentially movable denominational racks, two sets of denominational 105 wheels, one set of wheels being designed to represent a minuend introduced thereinto through said racks, and means whereby said set of wheels may be placed under control of the other set of wheels for the purpose of subtracting a number from said minuend, said means disabling the zero stops, so that said wheels representing the minuend may be reversely rotated past zero, if necessary.
46. In a calculating machine, the combination of differentially movable denominational racks, a set of denominational wheels in which a number representing a minuend may be introduced, another set of denominational wheels for controlling said first set 110 of wheels, and a key or lever for placing said last set of wheels in control of the first whereby a number may be subtracted from the minuend wheels.
47. In a calculating machine, the combination of differentially movable denominational racks, a set of wheels under control thereof and operable to add when stated in

one direction, and another set of wheels capable of being placed in control of the first mentioned set of wheels for reversely rotating the latter in subtracting operations and 5 means for permitting said wheels to move past their zero position in such reverse rotation.

48. In a calculating machine, the combination of differentially movable denominational racks, a set of denominational wheels operable through the instrumentality of said racks to add when rotated in one direction, another set of denominational wheels, and a key or lever for placing the 15 second set of denominational wheels in control of the first whereby said first set of wheels may be reversely rotated in the operation of subtraction.

49. In a calculating machine, the combination of differentially movable denominational racks, a set of denominational wheels operable in one direction to add, another set of denominational wheels operable in one direction to add, and a key or lever for placing the second set of wheels in control 25 of the first whereby when said second set of wheels are reversely rotated to be returned to zero, the first set of wheels will likewise be reversely rotated and the number represented in the second set of wheels will 30 be subtracted from the number represented in the first set of wheels.

In testimony whereof I hereunto affix my signature in the presence of two witnesses, this 28th day of June, 1909.

HUBERT HOPKINS.
